(57) **CLAIM**

The ornamental design for an intermediate adapter for a camera, as shown and described.

DESCRIPTION

FIG. 1 is a perspective view of an embodiment of an intermediate adapter for a camera showing my new design;

FIG. 2 is a rear elevational view thereof;

FIG. 3 is a top plan view thereof;

FIG. 4 is a bottom plan view thereof, rotated 180 degrees relative to FIG. 3;

FIG. 5 is a right side elevational view thereof; and,

FIG. 6 is a left side elevational view thereof.

The features shown in broken lines in the drawings depict environmental subject matter only and form no part of the claimed design. The dot-dashed lines denote the boundary of the claim and form no part of the claimed design.
